BUTTER SLICER

Charles A. Winslow, Ponca City, Okla.

Application January 10, 1936, Serial No. 58,508

2 Claims. (Cl. 31—20)

This invention relates in general to cutting devices and in particular to a butter cutter in which a block of butter, positioned on a base, is severed by a cutting member having a plurality of spaced wires to produce a plurality of equal slabs or cakes of butter for table or restaurant use.

The objects of the invention are, first; to provide a butter slicer of inexpensive construction, 10 efficient and simple in operation and suitable for use either in the home or in restaurants.

Second; to provide a cutting device in which the cutting means or wires are secured to a pair of rails or angles in a novel manner, said rails 15 being removably mounted to a support or carrying member.

Third; to provide a cutting device of the class described in which the cutting wires are spaced from the bottom of the cutting member, and 20 guide means are provided on the cutting member for allowing the cutter to be properly positioned on the block of butter before the wires contact the butter preparatory to the severing operation.

Fourth; to provide a cutting device of the class 25 described in which the cutting wires may be strung on a suitable carrying member provided with means for adjusting the tension of the wires.

These and further objects will be apparent by 30 reference to the following description in connection with the accompanying drawings, it being understood that modifications in form, proportion and minor details of construction may be resorted to without departing from the spirit of 35 my invention.

In the drawings:

Fig. 1 is a disassociated, perspective view of one form of my invention, parts being broken away to better illustrate certain other parts.

Fig. 2 is a cross sectional view through the device.

Fig. 3 is a fragmentary, longitudinal, sectional view through the device preparatory to depressing the cutter on the block of butter.

Fig. 4 is a perspective view of the rails carrying the cutting wires.

Fig. 5 is an enlarged detail sectional view through one of the wire carrying rails.

Fig. 6 is a disassociated, perspective view of 50 a modified form of slicer, parts being broken away to better illustrate certain other parts.

Fig. 7 is a fragmentary top plan view of the modified slicer.

Fig. 8 is a vertical, cross sectional view on the 55 line 8—8 of Fig. 7.

Fig. 9 is a fragmentary, longitudinal, sectional view on the line 9—9 of Fig. 7.

Referring now to the drawings by numerals of reference, 1 designates a sub-base having an upstanding portion or butter receiving base 2 upon which the block of butter 3 is placed. The cutting assembly includes a carrier 4 having a vertical, longitudinal opening or well 5 and handle portions 5'. At the bottom of carrier 4, wire carrying members or rails 6 are secured by means of screws 6' or other suitable fastening. Transverse cutting wires 7 are secured to and spaced equidistant on the rails 6. In Fig. 5 is shown one method of carrying the wires 7 on the rails 6, the wires passing through openings 7' in said rails, solder or other suitable material being flowed into the space 7" to seal the wires 7 in place.

At the ends of the carrier 4 are depending portions 8, of approximately the same height as 20 the base 2 so as to prevent undue strain on the cutting wires, since they will rest lightly on top of the base 2 at the completion of the severing operation. (See Fig. 2.) It will be noted that the wires 7 are fastened to the rails 6 near the 25 top thereof, and when the rails are assembled to the carrier 4, the wires will be spaced from the bottom of the cutting assembly which is now the bottom of the rails. The rails 6 provide longitudinal means for guiding the cutter onto the 30 block of butter.

In the operation of the device, the slab of butter 3 is placed on the base 2, the cutting assembly is guided onto the butter first by depending portions 8 and then by the longitudinal rails 35 6 until the cutting wires 7 rest on the butter. Further downward pressure on the cutter will cause the butter to be severed into a plurality of equal slices or cakes which will now be positioned in the opening or well 5, the depending portions 40 8 resting against the sub-base 1 and the cutting wires 7 resting lightly against the top of base 2. The carrier 4 may be raised and inverted over any suitable container to allow the butter slabs to gravitate thereinto. By this means butter can be supplied to the table in individual 45 cakes as needed, keeping the remainder of the butter in a cool place where it will not get stale.

In the modification shown in Figs. 6, 7, 8 and 9, means have been provided for rendering the cutting wires taut. The sub-base 1 and upstanding portion or base 2 to receive butter 3 are identical with that previously described.

The cutting member comprises a frame 10 having spaced wire receiving lugs 11 and handle por- 55

tions 12, the frame 10 being preferably formed of one piece and of a resilient material. A butter casing 13 is provided and is formed of two identical sections 14, the lower edges of the longitudinal sides 15 being securely fastened to frame 10 and have spaced perforations 15' providing passage for the cutting wires 16 which are positioned transversely of frame 10 and pass around lugs 11. The end walls 17 of the casing 13 are movable in relation to the end 18 of the opposite section 14.

Positioned transversely of frame 10 at each end thereof are adjusting members 19 comprising portions 20 and 21, having a gap 22 therebetween, a set screw 23 being threadedly engaged in member 21 and bearing against end of member 20 to provide means for increasing or decreasing the gap 22 to vary the tension of the cutting wires 16, said portions 20 being secured to end walls 17 of the casing 13. The ends of the cutting wires may be secured under the heads of the set screws 23. It will be readily seen that with this construction, the wires may be quickly strung on frame 10 and after the device is finally assembled, the set screws 22 may be turned to adjust the wires 16 to proper tension.

In actual practice it has been found that wood, and preferably maple, is the best material to be used for the carrier shown in the first form of my invention, since sufficient lubrication is provided by the butter to prevent same from adhering to the carrier when it is inverted for the removal of the butter therefrom.

It will be seen that I have provided a novel cutting or slicing device, inexpensive in construction and simple in operation, providing means for guiding the slicer onto the butter and means for adjusting the cutting wires to proper operating tension.

What I claim as new and desire to secure by Letters Patent is:—

1. The combination, in a cutting device of the class described, of a cutting member having cutting elements spaced from the bottom thereof, the portion of the cutting member between the cutting elements and the bottom of said cutting member forming a guide for positioning the cutter on the article to be cut, and portions at the ends of said cutting member depending lower than the side portions of the cutting member to form additional guides.

2. A cutting device of the class described comprising a plurality of spaced cutting elements, a longitudinal frame for supporting said elements, an article receiving chamber upstanding from the element supporting frame, the cutting elements being secured at the top of the cutting element supporting frame, whereby the frame will form a guide for positioning the cutter on the article being cut, and cutting element tensioning means, said article receiving chamber being adjustable with the element tensioning means, the cutting element tensioning means being positioned transversely of and below the element supporting frame whereby said cutting element tensioning means comprise end guide members for positioning the cutter on the article being cut.
